(74) Attorney, Agent, or Firm — Peter A. Sullivan;
Stephen J. Kenny; Foley Hoag LLP(57) CLAIM

The ornamental design for a bracelet, as shown and described.

DESCRIPTION

FIG. 1 is a perspective view of the bracelet showing my new design.

FIG. 2 is a front view thereof.

FIG. 3 is a back view thereof.

FIG. 4 is a bottom view thereof.

FIG. 5 is a top view thereof.

FIG. 6 is a right view thereof; and,

FIG. 7 is a left view thereof.

The broken lines in the drawings represent portions of the bracelet that form no part of the claimed design.
